[57] CLAIM

The ornamental design for a combined shower stall foot stool and storage compartment, substantially as shown and described.

DESCRIPTION

FIG. 1 is a perspective view of a combined shower stall foot stool and storage compartment showing my new design;

FIG. 2 is a perspective view thereof, the cover is shown in open position;

FIG. 3 is a front elevational view thereof;

FIG. 4 is a side elevational view taken from the right of FIG. 1;

FIG. 5 is a rear elevational view thereof;

FIG. 6 is a perspective view of a second embodiment, the only difference being the addition of an outline of a footprint located on the top of the cover.

The undisclosed bottom is plain and unornamented.

FIG. 6

FIG. 1

FIG. 5

FIG. 4

FIG. 3
